COLLAPSIBLE INFLATING DEVICE

Victor H. Hurt, Cranston, R. I., assignor to United States Rubber Company, New York, N. Y., a corporation of New Jersey

Application November 8, 1945, Serial No. 627,423

3 Claims. (Cl. 230—1)

1

This invention relates to collapsible devices for inflating large volume, low pressure articles such as mattresses and large toys.

It is possible to use a hand operated pump to inflate an air mattress or a large water toy but this is a slow tiresome operation. A quicker and more practical means for inflating such large low pressure articles is desired.

The present invention relates to a collapsible bag-like inflating device which is adapted to force air rapidly into the articles to be inflated, and which inflating device when not in use can be rolled up into a compact package.

One feature of the collapsible bag-like inflating device of the present invention resides in its open end construction whereby such end may be opened wide to extend the sides of the bag and allow a large amount of air to enter the bag, whereupon this end may be quickly closed and rolled upon the bag to squeeze the air trapped in the bag into the receptacle to be inflated.

Another feature of the present invention resides in a bag spreader that is secured in the bag near the opposite end thereof so as to facilitate spreading the bag in a wide open condition when it is to be filled with air.

The bag-like inflating device of the present invention may be constructed to be removably secured to the receptacle to be inflated and disengaged therefrom when the inflating operation is completed, or it may be permanently secured to the receptacle to be inflated. In either case this bag-like device may be rolled up into a compact package when not in use.

The above and other features of the present invention will be more fully understood from the following description when read in connection with the accompanying drawings, wherein:

Fig. 1 is a perspective view of an inflated water toy having the bag-like inflating device of the present invention removably secured thereto.

Fig. 2 is a perspective view showing the inflating device of Fig. 1 removed from the toy and having its open end fully extended so that the bag will fill quickly with air.

Fig. 3 is a perspective edge view of an end portion of the bag.

Fig. 4 is a perspective view of a pneumatic mattress having a bag-like inflating device somewhat similar to that shown in Fig. 2 permanently secured to one end of the mattress; and

Fig. 5 is a view similar to Fig. 4 except that the bag is shown as rolled up into a small space.

The bag-like inflating device of the present invention may be employed to inflate large water

2

toys, large balls, air mattresses and other collapsible low pressure pneumatic articles.

This inflating device as shown in Figs. 1 and 2 of the drawing is adapted to be removably secured to the receptacle to be inflated and is therefore provided with a tube at one end adapted to be removably secured to such receptacle; and the inflating device as shown in Figs. 4 and 5 of the drawing is permanently secured to the pneumatic article to be inflated and does not employ the tube connection means shown in Figs. 1 and 2.

Referring first to Figs. 1 and 2 of the drawing, there is shown in Fig. 1 a large pneumatic water toy such as a toy horse 10. This toy is provided at any convenient point, such as near the front end thereof, with a threaded socket 11 leading to the interior of the body 10 and having secured to its inner end a one-way valve such as the flutter valve 12. The socket 11 is adapted to receive a threaded tube 13 attached to one end of the collapsible bag-like inflating device 14 as shown in Fig. 2. The arrangement is such that the inflating bag 14 can be easily and quickly attached to the pneumatic receptacle 10, when the latter is to be inflated, by screwing the tube 13 into the socket 11.

Since the primary purpose of the present invention is to provide means whereby large low pressure pneumatic devices may be easily and quickly inflated, the inflating bag 14 is so constructed that it can be easily and quickly filled with air and then closed to trap this air in the bag so that it may be forced into the pneumatic receptacle. This is accomplished by providing the bag 14 at its end which is remote from the tube 13 with a wide open end that extends entirely across the bag, and in order to facilitate closing this end of the bag, such open end has extending along the opposite side walls thereof adjacent the opening the flexible stiffening strips 15 which are adapted to be brought together to form a bar upon which this end portion of the bag may be rolled. It will be apparent from Fig. 1 that after these strips 15 are brought together they will form a bar extending throughout the entire width of the bag and upon which this portion of the bag may be rolled by hand as indicated at 16, and thereby squeeze the air which has been trapped in the bag through the tube 13 into the receptacle to be inflated.

If the bag 14 is to have a wide end that can be quickly and tightly closed so that air will not leak from this end under pressure, it is important that this end portion of the bag be carefully constructed as will now be described. The stiffen-

ing strips 15 should extend entirely across the width of the bag as shown and should be sufficiently flexible to allow this end of the bag to be forced wide open as shown in Fig. 2 so that air may rush into the bag to fill the same. As soon as the bag is full the strips 15 may be brought together into parallel contacting relation with each other to close the bag and form a bar upon which this end of the bag may be rolled. This rolling action tends to shift one strip 15 laterally 10 relative to the other, and to prevent this one of the strips 15 is preferably provided with the folded over portion 17 that is best shown in Fig. 3 and which forms a pocket that receives the other strip 15 and helps to keep this end of the bag closed. It is difficult to prevent the creased side walls of the bag from leaking adjacent the ends of the strips 15 since air will tend to escape from inside the bag along the folded crease lines. To prevent air from escaping along these folded seams such seams are sealed with an adhesive for a short distance as indicated by 18.

The opposite end of the bag 14 is provided with a conical shaped member 19 having an apex to which the threaded tube 13 is secured. The conical member 19 is secured to the bag 14 by the seam 20. In order that the bag may be fully opened as shown in Fig. 2 to receive a large quantity of air it is important to provide inside of the bag near the seam 20 a spreader 21 which may consist of a hollow rectangular frame conveniently formed of spring wire, or of a partition having a large central opening so that the bag will normally remain extended adjacent its conical end 19 as shown in Fig. 2.

In some cases, as above stated, the bag-like inflating device of the present invention may be permanently secured to the pneumatic device to be inflated. Such a construction is shown in Figs. 4 and 5 wherein there is illustrated a pneumatic mattress 22 having the longitudinally extended inflated cells 23, and one end of this mattress has permanently secured thereto the bag-like inflating device 24 which may be similar to the bag-like device 14, except that in the construction of Figs. 4 and 5 the conical end 19 of the bag is omitted as this end of the bag is permanently secured in a widely spread condition to one end of the mattress by the seam 25. By securing an end of the bag 24 directly to the mattress 22 so that this end is retained in a widely spread condition, it is unnecessary to provide the bag shown in Figs. 4 and 5 with a spreader similar to the spreader 21 shown in Figs. 1 and 2. The bag 24 operates the same as the bag 14 to force air rapidly into the pneumatic receptacle to be inflated. That is, after the bag 24 has been opened wide by separating the strips 15 to fill the bag with air, this end may be closed and rolled upon itself as indicated by 26 so as to force air into the receptacle to be inflated as the rolling operation is continued. Air is forced from the bag 24 into the mattress through a one-way flutter valve 27. After the bag 24 has been rolled

up into a compact package it may be covered by the mattress flap 28 to form a pillow at one end of the mattress. This flap 28 can be secured in its closed position by the snap-fasteners 29.

It will be seen from the foregoing that the collapsible bag-like inflating device of the present invention can be used to inflate quickly large low pressure pneumatic devices, and when not in use can be rolled up into a small compact package.

Having thus described my invention, what I claim and desire to protect by Letters Patent is:

1. An inflating device for inflating a collapsible receptacle with air, comprising a bag that is rectangular in cross section and having one end permanently attached to the receptacle to be inflated and a wide rectangular opening at its other end through which air may enter quickly to fill the bag, the open end having flexible stiffening strips extending along the long side walls of the bag and adapted when brought together to form a bar upon which this end portion of the bag may be rolled to close the bag and squeeze the air therein into the receptacle, and means for holding one strip from shifting relative to the other during such rolling action.

2. An inflating device for inflating a receptacle with air, comprising a bag that is rectangular in cross section and having one end permanently attached to the receptacle to be inflated and a wide rectangular opening at its other end through which air may enter to fill the bag quickly, the open end portion of the bag having opposite flat seams extending lengthwise of the bag and flexible stiffening strips extending along the opposite side walls of the bag from one seam to the other and adapted when brought together to form a bar upon which this end portion of the bag may be rolled to close the bag and squeeze the air therein into the receptacle.

3. An inflating device for inflating a collapsible receptacle with air, comprising a bag that is rectangular in cross section and having one end permanently secured to the receptacle in a widely spread condition and having a wide opening at its other end through which air may enter to fill the bag when it is held with its side walls spaced widely apart, flexible stiffening strips extending along the opposite side walls of the bag at its open end and adapted when brought together to form a bar upon which this end portion of the bag may be rolled to close the bag and squeeze the air therein into the receptacle.
